UNITED STATES PATENT OFFICE

2,472,836

REVERSIBLE PROPELLER

Earnest R. Kennedy and Lowell E. Kennedy,
Defiance County, Ohio

Application July 31, 1946, Serial No. 687,451

1 Claim. (6Cl. 170—160.32)

1

The present invention relates to new and useful improvements in propellers and more particularly to marine propellers and the invention has for its primary object to provide means for reversing the pitch of the propeller blades to thus provide for a forward and reversing drive for the propellers.

An important object of the present invention is to provide a hydraulically operated reversing mechanism for the blades of the propeller.

A further object of the invention is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a longitudinal sectional view through the hub of the propeller and showing the control valve for reversing the pitch of the blades of the propeller.

Figure 2 is a sectional view taken on the line 2—2 of Figure 1.

Figure 3 is a transverse sectional view taken on a line 3—3 of Figure 1 of the coaxial fluid inlet and outlet tubes and

Figure 4 is a perspective view of the reciprocating piston for reversing the blade.

Referring now to the drawings in detail, wherein for the purpose of illustration, we have disclosed a preferred embodiment of the invention, the numeral 5 designates the propeller hub generally which includes a ring member 6 closed at its ends by end plates 7 and 8 secured to the ring by bolts or the like 9.

A pair of propeller blades are shown at 10 which are formed at their inner ends with a flanged stub-shaft 11 journaled in diametrically opposite sides of the ring 6. A pin 12 projects inwardly at the inner end of the stub-shaft 11 eccentrically to the axis thereof and is received in a circumferential groove 13 of a piston 14, preferably of square-shaped construction as shown in Figure 4 of the drawing and is slidably positioned in a correspondingly shaped chamber 15 formed on the inside of the ring 6.

A tube 16 extends through the end plates 7 and 8 and also through a central opening 17 in the piston 14 for sliding action of the piston in the chamber on the tube. The tube is formed

2

with a pair of lateral ports 18 and 19 communicating with the chamber 15 at opposite sides of the piston.

A cylindrical valve 20 is slidably mounted in the tube 16 having a longitudinally extending passage therein extending from end to end of the valve communicating with a pair of lateral passages 22 and 23 adjacent the front end of the valve, the outer ends of the passages 22 and 23 terminating in circumferential grooves 24 and 25, respectively in the valve. The grooves 24 and 25 are arranged to alternately register with the port 18 of the tube 16.

The rear end of the valve 20 is formed with a longitudinal passage 26 adjacent one side thereof with which a pair of lateral passages 27 and 28 communicate, the rear end of the passage 26 being open at the end of the valve for communicating with the tube 16. The lateral passages 27 and 28 are arranged to alternately register with the port 19 of the tube 16.

An apertured guide or spider 29 is secured in the tube 16 behind the valve 20 and through which a smaller inner tube 30 extends for positioning longitudinally in the larger outer tube 16, the front end of the tube 30 being slidably received in the rear end of the passage 21. A coil spring 31 is positioned on the tube 30 between the guide 29 and the rear end of the valve 20 and a coil spring 32 is positioned between the front end of the valve 20 and a plug 33 secured in the front end of the tube 16, the springs 31 and 32 cooperating to maintain the valve 20 in a neutral position in the tube 16 with the passages 22 and 23 out of registry with the port 18 and with the passages 27 and 28 out of registry with the port 19.

In the operation of the device the tubes 16 and 30 communicate with a common source of fluid pressure having suitable control means (not shown) for supplying fluid under pressure to the chamber 15 through either of the tubes, the other tube constituting a return line.

When fluid pressure is supplied to the inner tube 30 the fluid will enter the passage 21 for acting against the front end of the valve 20 whereby the valve is moved rearwardly in the tube 16 to register the passage 22 with the port 18 and exert its influence against the front side of the piston to move the same rearwardly in the chamber 15.

The rearward movement of the piston will carry the pin 12 with it, which by reason of its eccentric position at the inner end of the shaft 11 will rotate the shaft to reverse the position of the

blades 10. At the same time the passage 27 will register with the port 19 and permit the exhausting of the fluid from behind the piston through the tube 16 to the supply.

Release of the pressure against the front end of the valve will enable the springs 31 and 32 to return the valve to its neutral position and the blades will be held in their adjusted position.

A reverse movement of the blades is obtained by admitting fluid under pressure through the tube 16 behind the valve 20 thereby sliding the valve forwardly to register the passage 28 with the port 19 to subject the rear of the piston 14 to fluid pressure to thus slide the piston forwardly in the chamber 15 and at the same time register the passage 23 with the port 18 for return of the fluid at the front end of the chamber through the tube 30.

The hub 5 may be connected to a drive shaft (not shown) in any suitable manner.

In view of the foregoing description taken in conjunction with the accompanying drawings it is believed that a clear understanding of the construction, operation and advantages of the device will be quite apparent to those skilled in the art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

We claim:

A reversible propeller comprising a housing having a chamber therein, a pair of propeller blades each including a root journaled in diametrically opposite sides of the housing, a piston

working in the chamber, interconnecting means between the roots and the piston operable to transmit reciprocating movement of the piston to rotary movement of the root to vary the pitch of the blades, a tube extending through the housing having ports communicating with the chamber at opposite sides of the piston and adapted to subject the piston to fluid pressure, said piston being slidable on the tube, a sliding reversing valve in the tube controlling the ports in the tube to oppositely actuate the piston, said valve having a passage therethrough, and a fluid pressure supply pipe connected to the passage at one end of the valve to supply fluid pressure behind an opposite end of the valve to move the valve in one direction, the first named end of the valve being subjected to fluid pressure in the tube to move the valve in an opposite direction, and said tube and said supply pipe alternately providing fluid pressure supply and return conduits for the chamber upon reversing of the valve.

EARNEST R. KENNEDY.
